(No Model.)

R. BEAN.
FORCE PUMP.

No. 372,888.

Patented Nov. 8, 1887.

UNITED STATES PATENT OFFICE.

ROSCOE BEAN, OF SPRINGFIELD, OHIO, ASSIGNOR TO MAST, FOOS & COMPANY, OF SAME PLACE.

FORCE-PUMP.

SPECIFICATION forming part of Letters Patent No. 372,888, dated November 8, 1887.

Application filed October 4, 1886. Serial No. 215,265. (No model.)

To all whom it may concern:

Be it known that I, ROSCOE BEAN, a citizen of the United States, residing at Springfield, in the county of Clark and State of Ohio, have 5 invented certain new and useful Improvements in Force-Pumps, of which the following is a specification, reference being had therein to the accompanying drawings.

This invention relates to improvements in 10 force-pumps; and the invention consists, first, in closing the upper end of that part of the barrel which constitutes the cylinder proper by means of a removable head or cap, in a plunger which acts below the head, and in 15 constructing the cylinder with a discharge-opening between the head and the plunger, whereby the water is resisted when drawn up by the plunger, so as to form a force-pump without the use of an inner cylinder and another 20 plunger, or of the usual enlarged piston, both which serve to form a partial vacuum or water-space at the downward movement of the handle and to displace the water on the reverse movement thereof; and whereby, also, the water 25 is given a place of exit other than through the head.

The invention consists, secondly, in combining the removable head with an attachment, either a rod or tube, which extends to within 30 reach from the platform and is secured so as to suspend the head and support it.

The invention also consists, thirdly, of a barrel or upper extension of the cylinder proper of sufficient diameter to permit of the withdrawal of the head and plunger, &c., through it, when combined with a stock supported by the platform and constructed to receive and strongly hold or bind the barrel.

In the accompanying drawings, forming a 40 part of this specification, and on which like reference-letters indicate corresponding features, Figure 1 represents an elevation of my improved pump, showing the lower portion thereof in section; Fig. 2, a detached plan view 45 of the stock-cover; Fig. 3, a transverse sectional view on the line $\alpha\alpha$ of Fig. 4; Fig. 4, a vertical sectional view of the upper end of the barrel and the cover, showing also one section of the stock; Fig. 5, a side elevation of the same 50 parts, and likewise illustrating one section of

the stock; and Fig. 6, a transverse sectional view of the two-part stock, showing the line of division between said parts, the view being taken on the line yy of Fig. 4.

The letter A designates a platform or curb 55 at the mouth of the well, and the letter B a metallic stock of cylindrical form, and preferably constructed in two vertical parts held together by the lugs and bolts C, and fashioned at its lower end to set firmly upon the platform. Each part has a vertical standard, D, (one only appearing,) and both constituting 60 the fulcrum-support for the handle. The barrel D' is fitted to the cylindrical interior of the stock, and when the two parts are drawn 65 tightly together by the bolts they clamp and strongly secure the barrel. This pump is contemplated to form a deep-well pump, as well as one for shallow wells, and in case the frictional contact in the former instances should 70 not prove sufficient to sustain the weight, I provide the barrel with a band, E, adapted to be shrunk thereon, and having lugs F, which enter recesses in the parts of the stock, as seen in Figs. 4 and 5.

The letter G indicates the cover, which fits upon the stock and is held in any convenient manner, and has a flange entering and fitting the barrel, as seen in Figs. 3 and 4. This cover has a screw-threaded recess in the under side, and in this recess is screwed the upper end of the attachment H, which supports the removable head I. This attachment may of course be secured in some other way; but it is desirable that it should be within reach 80 of a person standing on the platform, whereby it may be withdrawn, together with the removable head I, to permit of the withdrawal of the piston and plunger. The attachment is either a rod or a tube, and when the latter 85 it serves also as an air-chamber. From a point in proximity with the position of the removable head I downward the barrel becomes a cylinder in function, and by the term "cylinder," as hereinafter used, such will be 90 the meaning. The removable head is preferably provided with a packing at its periphery, and is made to snugly fit the cylinder, to practically prevent the upward flow of the water as it is lifted or forced by the plunger. 95

This is the essential function of the head, while incidentally it prevents any gravel or other foreign matter which may fall into the barrel from finding its way to the cylinder. The cylinder proper is preferably constructed in sections J K, or more, for the purpose of lengthening it to suit wells more or less deep, and so as to convert a shallow-well pump into a deep-well pump. These sections are held together by means of screw-threaded sleeves L.

The letter M indicates the piston-rod, which may be either tubular or solid. When the former, it is sufficient if the hollow portion begins at about the point N, where an opening 15 is formed, and extends thence upward any desired distance. Thus an air-chamber is formed which may be used in conjunction with or separately from the air-chamber, constituted, in some instances, by the attachment 20 H. A hole having a seat is formed in the head I, and a thimble, O, is applied, whereby a passage and a stuffing-box are afforded for the piston-rod. The cylinder, at a convenient point below the head and above the 25 plunger, is provided with a discharge, P, to which connects a discharge-pipe, O', passing up through the platform and terminating in a spout. The lower end of the cylinder has a valve of any approved construction.

30 The attachment may be held by other means than the cover, and I do not desire to be understood as limiting myself to the means shown alone. The piston-rod is constructed also in sections—as seen, for example, at Q—whereby 35 it may be lengthened to agree with the cylinder.

It should be noted that the essential function of the head I is to stop the upward escape of the water and to coact with the plunger 40 in securing a force-pump devoid of the inner cylinder or enlarged piston, as already hereinbefore explained. Furthermore, the presence of the discharge-passage between the head and the plunger is deemed of peculiar 45 virtue in contributing to this end. The removability of the head permits of its being withdrawn, and of the operating mechanism of the pump being also withdrawn from the platform above and without disturbing the structure 50 generally. It is preferred to support the cylinder by means of a barrel, but it is obvious that it may be supported by rods or otherwise. It should be also observed that the position of the head I is below the freezing-point, 55 so that there is never any accumulation of water as high as the freezing-point. The small quantity which may remain in the pipe O' after using the pump runs back into the cylinder below the head. This is of importance in keeping the pump free from ice.

I would here observe and have it understood that the idea of a removable head used in connection with a pump-cylinder is not now distinctively new, as the same may be seen in 65 Letters Patent of the United States issued to

me January 26, 1886, and numbered 334,732, for improvements in pumps. I would also have it understood that I am aware that pump-cylinders with lateral water-discharge openings are not distinctively novel.

Having thus fully described my invention, what I claim as new, and desire to secure by Letters Patent, is—

1. In a pump, the combination, with the cylinder constructed to be supported from the 75 platform above it and having a lateral discharge below the platform and the freezing-point, and a discharge-pipe leading from said discharge to and above the platform, of a removable head, which cuts off the upward rise of the 80 water located within the cylinder and below the freezing-point, and above the said discharge, an attachment connected to the head and extending to a point within reach from the platform, and a piston-rod working through 85 the head, and having a plunger within the cylinder and below the head.

2. In a pump, the combination, with a cylinder supported from the platform above it and provided with a lateral discharge located 90 below the platform and the freezing-point and having a pipe which leads to and above the platform, of a removable head, which cuts off the upward rise of the water located in the cylinder below the freezing-point, and above 95 the lateral discharge, a tubular attachment secured to the head at its lower end and extending within reach of the platform and there secured and closed to form an air-chamber, and a piston-rod having a plunger within the 100 cylinder and below the said discharge.

3. In a pump, the combination, with a cylinder and its support connected to it and extended to and above the platform and there secured, of a removable head located below 105 the freezing-point and constructed to cut off the upward rise of the water, and having a support which extends above and is secured within reach of the platform, whereby the head is held and may be withdrawn, a piston-rod working through the head, and having a 110 plunger below the head and a discharge for the water.

4. In a pump, the combination, with a barrel extended above and below the platform 115 and supported by the same, of a removable head located below the freezing-point and within the cylinder, and a support for said head connected to it and extended above it and secured within reach of the platform.

5. In a pump, the combination, with a divided cylindrical stock and a barrel fitted within the stock and clamped and held by it, of a cylinder secured to the lower end of the barrel, a removable head, which cuts off the 120 upward rise of the water and is located below the platform and forms a division between the cylinder and the barrel, and an attachment secured to the removable head at its lower end and at its upper end within reach of the platform, 125 130

whereby the head may be withdrawn and the operating mechanism also lifted out through the barrel.

6. In a pump, the combination, with a vertically-divided stock having a cylindrical interior and a barrel having an exterior corresponding in shape with the interior of the stock and fitted within and clamped and held by the stock, of a cylinder secured to the lower end of the barrel, the barrel being as large

interiorly as the interior of the cylinder, whereby the operating mechanism may be withdrawn.

In testimony whereof I affix my signature in presence of two witnesses.

ROSCOE BEAN.
